ABSTRACT OF THE DISCLOSURE

A forging press having a press frame and a flywheel eccentric shaft rotatable in the frame about a horizontal axis and having an eccentric portion surrounded by an eccentric ring swivelably connected to the forging head by a pressure-transmitting member which is seated in an upwardly concave socket of the forging head and has a center of curvature located within the inner periphery of the ring; the ring has an upper surface slidably bearing upon a portion of the forging slide, this portion having a center of curvature coinciding with the center of curvature of the swivel member.

My present invention resides in a forging press having a support frame, a workpiece-supporting anvil, and a vertically shiftable head which is displaced by an eccentric shaft carrying a flywheel.

Forging presses which make use of an upstanding support frame or stand in which an eccentric shaft or crank-shaft is journaled generally provide guide means for a vertically shiftable press slide carrying, at its lower end, the forging head of the press and rods or the like connecting the eccentric portion of the shaft to change the rotary motion of the shaft to linear motion of the slide toward and away from the anvil. The rods, pins and link members provided for this purpose must withstand considerable dynamic and static stress, vibration and shock and often are a weak point in the press construction. The rods also may be of considerable length and thus have the tendency to bulk or otherwise deform. Consequently, forging presses of this character require frequent repair, expensive and highly skilled maintenance and are of relatively expensive construction.

It is an object of the present invention to provide a forging press in which the aforementioned disadvantages can be avoided, relatively high dynamic forces can be applied to a workpiece without danger of damage to the moving parts, and which is of less expensive construction by comparison with earlier presses.

Still another object of this invention is to provide a force-transmitting system for a forging press or the like which transfers a maximum force or energy with a minimum of danger of breakdown or damage.

I have found that these objects can be obtained in a forging press which omits the force-transmitting rods, pins and bars required heretofore and which simplifies the means for converting rotation of a crankshaft into vertical reciprocation of the press slide. According to a specific feature of this invention, the press comprises a stand or frame in which the anvil is mounted and which forms a guide for a vertically reciprocating press slide whose lower portion forms the forging head. The drive means for this slide advantageously comprises an eccentric shaft journaled in the support or frame and rotatable about a horizontal axis while carrying the usual flywheel. Advantageously, the shaft extends through the slide in the vertical median plane of the latter and carries a cylindrical eccentric portion whose axis describes

2

a circle centered on the axis of rotation of the shaft and, moreover, establishes the vertical stroke of the slide. Surrounding this cylindrical eccentric, I provide a ring within which the eccentric cylinder is rotatable and which carries a force-transmitting swivel having a swivel body disposed directly between the cylindrical eccentric portion of the shaft and the forging head. This swivel body preferably has a downwardly convex portion of substantially cylindrical curvature which is received in an upwardly open trough or socket formed in the forging head complementarily to the cylindrical curvature of the swivel body. The mutually engaging surfaces of the socket and this body are centered upon the swivel axis which, advantageously, lies within the outer periphery of the cylindrical eccentric but is spaced from the axis of rotation of the shaft by a distance greater than that with which the axis of the cylindrical eccentric portion is distant therefrom. The pressure-transmitting body thus may be constituted as a partial or semicylinder although spherical or hemispherical shapes are also possible. Diametrically opposite the pressure-transmitting member, which is affixed directly to the eccentric ring and constitutes part thereof as indicated earlier, I provide a segmental abutment whose outer surface is also centered 25 on the axis of the swivel body and may engage a complementary portion of the press slide dovetailed in a traverse above the eccentric shaft. The slide surfaces are likewise centered on the swivel axis.

This system has the advantage that all pressure-transmitting rods, toggle levers and the like can be avoided and that force is transmitted with a maximum of directness from the shaft to the workpiece. In addition, minimum force is required to lift the slide from the workpiece during the return stroke and the forces applied to the traverse upon which the eccentric acts in the return stroke are relatively small.

The above and other objects, features and advantages of the present invention will become more readily apparent from the following description, reference being made to the accompanying drawing in which:

FIG. 1 is a vertical elevational view, partly in axial cross-section, of a forging press in accordance with the present invention;

FIG. 2 is a cross-sectional view along the line II—II of FIG. 1;

FIG. 3 is a cross-sectional view of a portion of the device of FIG. 2 showing the pressure-transmitting member in another position; and

FIG. 4 is a cross-sectional view along the line IV—IV of FIG. 1.

In the drawing, I show a forging press which comprises a press stand or frame 1 whose posts or legs 1a, 1b, etc. are held together by a solid crosspiece 1c and define guides in a conventional manner for the vertically shiftable press slide 3 which has a forging head 3a adapted to be advanced toward an anvil 2 and withdrawn therefrom during the press stroke. Through an opening 15 between the posts or legs 1a, 1b, etc., a workpiece may be inserted between the head 3 and the anvil 2 for forging action.

The drive for the slide 3 comprises an eccentric shaft 4 whose axis of rotation in the support 1 is represented at arrow A and which is driven by conventional means (e.g. a unirotational belt and pulley system, etc.) and is provided with a flywheel 16. Means for adjusting the throw of the crankshaft is constituted by the gears 17 and the control member 18 which function as described in my commonly assigned copending application (now abandoned) Ser. No. 713,376 filed concurrently herewith and entitled "Forging Press With Adjusting Means." The shaft 4 passes through the slide which is formed with a

traverse 10 across its top. At a central location along the shaft 4, the eccentric shaft is provided with an eccentric 5 whose cylindrical surface 5a is centered on the axis B offset radially from the axis A. The eccentric is surrounded by a ring 6 forming part of a force-transmitting swivel 6-8 which includes a solid body 7 of crescent-shaped cross-section. This body 7, which is welded to the balance of the ring 6, has an inner surface 7a corresponding to the outer cylindrical surface 5a and completes the ring 6. The body 7 constitutes the sole force-transmitting member between the eccentric 5 and the head 3a which is formed with an upwardly concave socket 19 in which the convex portion 8 of the body 7 is received. The surfaces of portion 8 and socket 19 are generally cylindrical and are centered upon the axis 13 which constitutes the swivel axis of the device and is spaced from the axis A by a distance greater than the distance of axis B therefrom. Diametrically opposite the body 7, ring 6 is provided with an abutment 9 of generally sectoral configuration whose surface 11 is complementary to the surface 12 of a slide 20 dovetailed in the traverse 10. Surfaces 11 and 12 are also centered upon the swivel axis 13.

During the operation of the press, rotation of shaft 4 about the axis A swings the axis B about the axis A to describe the circle C. The swivel means 6, 7 and 8 is thus deflected as represented at α from side to side as the slide is raised and lowered. In its extreme positions, the body 7 is aligned directly with the axis A, B and 13 (see FIG. 2) so that maximum force transmission is ensured. During the return stroke, member 9 acts against the traverse 10 to lift the slide. Best results have been found to be obtainable when the center of curvature 13 of the surface A lies within the surface 5a, i.e. with the eccentric 5.

I claim:

1. A forging press comprising an upright support, an anvil, a press slide vertically shiftable on said support toward and away from said anvil, said slide being formed with a forging head engageable with a workpiece disposed on said anvil, a shaft journaled on said support for rotation about an axis of said shaft and carrying a cylindrical eccentric with an axis spaced from the axis of the shaft and describing a circular path upon rotation of the latter, and force-transmitting swivel means engaging said eccentric and connected with said head while including a solid force-transmitting body interposed

5 directly between said eccentric and said head, said force-transmitting swivel means comprising a ring surrounding said eccentric with said eccentric being rotatable within said ring, said body being affixed to said ring, said ring and said body defining a swivel axis spaced from the axis of said shaft and said eccentric, said body having a convex portion centered on said swivel axis and said head being formed with a concave socket complementarily receiving said convex portion, said socket and said convex portion having mutually contacting surfaces centered on said swivel axis and said swivel axis lying within the outer periphery of said eccentric.

2. A forging press as defined in claim 1 wherein said mutually contacting surfaces are generally cylindrical.

15 3. A forging press as defined in claim 1 wherein said mutually contacting surfaces are generally spherical.

4. A forging press as defined in claim 1 wherein said ring is formed at a location diametrically opposite said body with an arcuate bearing surface acting upon said slide for movement thereof away from said anvil, said surfaces being centered on said swivel axis.

20 5. A forging press as defined in claim 4 wherein said slide is formed with a traverse engageable by said bearing surface.

25 6. A forging press as defined in claim 1 wherein said swivel axis is spaced from the axis of rotation of said shaft by a distance greater than the distance between the axis of said shaft and the axis of said eccentric.

30 7. A forging press as defined in claim 1 wherein said shaft passes through said slide and is provided with a flywheel.
